UNITED STATES PATENT OFFICE

142,532

DESIGN FOR A SHOE HEEL

Eduardo Juan Scherini, Rosario, Argentina,
Application June 2, 1945, Serial No. 119,871

Term of patent 7 years

(Cl. D7—5)

To the Commissioner of Patents:

Be it known that Eduardo Juan Scherini, a citizen of the Argentine Republic, and resident of the Borough of Rosario, Province of Santa Fé, Argentine Republic, has invented a new, original, and ornamental Design for Shoe Heels, of which the following is a specification, reference being had to the accompanying drawing, forming part thereof.

The figure is a bottom perspective view of a shoe heel showing my new design, the opposite side presenting substantially the same appearance as the side shown.

I claim:

The ornamental design for a shoe heel, as shown and described.

EDUARDO JUAN SCHERINI.
